CLAIM

The ornamental design for a rammer as shown and described.

DESCRIPTION

FIG. 1 is a front view of a rammer showing our new design;
FIG. 2 is a right side view thereof;
FIG. 3 is a rear view thereof;
FIG. 4 is a bottom view thereof;
FIG. 5 is a left side view thereof;
FIG. 6 is a top view thereof; and,
FIG. 7 is a front and right perspective view thereof.
The broken lines shown are for the purposes of illustrating the environment of the article only and form no part of the claimed design.

1 Claim, 7 Drawing Sheets
